UNITED STATES PATENT OFFICE.

CHARLES W. BECK, OF DETROIT, MICHIGAN, ASSIGNEE TO THE BECK-FROST CORPORATION, A CORPORATION OF MICHIGAN.

METHOD OF FORMING RIMS FOR STEERING-WHEELS.

1,262,797.

Specification of Letters Patent. Patented Apr. 16, 1918.

Application filed October 26, 1914. Serial No. 868,723.

To all whom it may concern:

Be it known that I, CHARLES W. BECK, a citizen of the United States of America, residing at Detroit, in the county of Wayne and State of Michigan, have invented certain new and useful Improvements in Methods of Forming Rims for Steering-Wheels, of which the following is a specification, reference being had therein to the accompanying drawings.

The invention relates to a new and improved method of shaping vulcanized fiber and resides in certain novel steps in the method as will more fully hereinafter appear.

In the present state of the art vulcanized fiber has been formed in sheets, and these sheets have been employed for making straight tubes or other shapes that can be readily fashioned from the sheets without remolding the fibrous material. This invention has among the objects thereof to provide a method whereby the vulcanized fibrous material may be made into such shapes as required.

Generally speaking my improved method consists in shaping in the form desired, the fiber after it has been vulcanized but while the fibers are still green, and then permitting the fibrous material to dry sufficiently to maintain its shape while in engagement with the mandrel, mold or other shaping device.

While the invention is adapted for making various types of articles, for the sake of clarity I will illustrate and describe the invention in connection with the formation of rims of steering wheels.

In the drawings,—

Figure 1 is a horizontal section of a rim made by my improved method;

Fig. 2 illustrates a different form of rim made by the improved method;

Figs. 3, 4 and 5 illustrate certain details;

Fig. 6 is a section through a tube after it has been shaped;

Fig. 7 illustrates a curved mandrel;

Fig. 8 is a top plan view, partly in section, of a modification; and

Fig. 9 is a sectional perspective view illustrating a mold into which the improved method may be carried out.

In making a rim by my improved method, a tube is formed of fibrous material, preferably by winding fibrous material upon a suitable mandrel and vulcanizing, and while

the fibrous material is still green it is bent into the desired form and then allowed to dry sufficiently to retain its shape. Preferably the fibrous material is wound upon a straight mandrel, thereby forming a straight tube. The latter is then removed from the mandrel while the fibers are still green, the chemical solution washed from the fibrous material and the tube then telescoped upon a mandrel of segmental form, the curvature of the mandrel being substantially that desired for the vehicle rim. The fibrous tube is preferably allowed to remain upon the curved mandrel until sufficiently dry to maintain its shape, and is then removed. After the green tube is telescoped upon the curved mandrel, any creases or the like may be eliminated by ironing, or by any other suitable process.

Instead of shaping the green tube by forcing it over a curved mandrel, the green tube may be subjected to molds shaped by hand, or otherwise suitably formed. Also when an inner rim member is employed the fibrous tube when removed from the straight mandrel, is telescoped upon the inner rim member and allowed to shrink thereupon to form a permanent covering therefor. During setting or hardening of the vulcanized fiber there is a tendency for it to contract. I therefore find it desirable to form the rim of a plurality of segments, the ends of the segments being connected together in any suitable manner. In some instances, however, the rim may be formed of a split ring.

In the drawings, Fig. 1 illustrates a rim made of two segments A and B, each formed solely of fibrous material by forcing a green straight tube as C in Fig. 6 over a curved mandrel as D shown in Fig. 7. The meeting ends of the sections A and B are connected together by means of a filler member E formed of wood or other suitable material and to which the ends of the spider arms F are attached. The filler block is preferably glued and nailed to the meeting ends of the segments, but may be attached thereto in any desirable manner. The outer ends of the arms are shaped to form segmental bearings to receive the rim. Preferably two of the arms are connected to the rim at the junction of the segments, as by means of screws which pass through the rim and through the blocks E. If desired a segmental bearing may be employed for the upper face of

the rim. In some instances, instead of securing the ends of the intermediate arms F' to the rim, as shown in Figs. 1 and 4, a filler member e is arranged intermediate the ends 5 of the segments to form a more rigid attachment for the outer end of the spider arms F'. The member e is of sufficient size to allow it to be telescoped within the segmental tube after the latter has dried.

10 In the construction shown in Fig. 8, an inner rim G of tubular metal is provided, this metal tube serving to shape the green tube when the latter is applied thereto as hereinbefore described. With the arrangement shown in Fig. 8, the ends of the tubular metal sections may be connected together by a metallic band H.

Instead of shaping the fibrous material upon a mandrel, it may—as before stated—20 be shaped in a mold and in Fig. 9 I have illustrated one manner of forming the fibrous material by means of a mold. Thus I and J are two sections of a sheet metal mold, of segmental form, and K is the 25 fibrous material. The latter is made into tubular form and one end thereof closed by means of a stopper L or other suitable means, while the opposite end is attached to the compressed air supply connection f. After 30 the fibrous tube has been engaged with the mold and the sections thereof clamped closed as by means of a clamp g, compressed air is admitted to the fibrous tube, which will cause the latter to assume the shape of the 35 mold. The mold is herein shown as having a plurality of corrugations M on the inner face thereof and of a contour to form a sec-

tion of a steering wheel rim. After the fibers of the material have set or hardened sufficiently to retain its shape, the material 40 is removed from the mold.

While I have shown and described several very desirable forms of rim which may be made by my improved method, it will be understood that not only is the method 45 adapted for the formation of rims of various types, but also articles of various contours can be made thereby.

What I claim as my invention is:—

1. The method of forming rims of steering wheels from vulcanized fibrous material, comprising forming the vulcanized fiber into tubular stock and in shaping the vulcanized stock by a form into the desired contour when the fibers of the stock are pliable, and 55 in allowing the fibrous material to dry and in then finishing the surface of the fibrous material.

2. The method of forming rims of steering wheels from vulcanized fibrous material, 60 comprising forming a comparatively straight tube of vulcanized fibrous material and changing the shape of the tube into segmental form, and shaping the tube by means operating from its interior when the fibers 65 of the vulcanized tube are still pliable and then finishing the surface of the rim.

In testimony whereof I affix my signature in presence of two witnesses.

CHARLES W. BECK.
